DESIGN FOR A WEATHER VANE

Junius F. Royals, Godwin, N. C.

Application August 4, 1945, Serial No. 121,231

Term of patent 7 years

(Cl. D52—7)

To all whom it may concern:

Be it known that I, Junius F. Royals, a citizen of the United States and resident of Godwin, county of Cumberland, and State of North Carolina, have invented a new, original, and ornamental Design for Weather Vane, of which the following is a specification, reference being had to the accompanying drawing, forming part thereof.

In said annexed drawing:

Fig. 1 is a side elevation of the weather vane showing my new design,

Fig. 2 is a front elevation of the weather vane showing my new design,

Fig. 3 is a plan view of the weather vane showing my new design.

I claim:

The ornamental design for a weather vane, as shown.

JUNIUS F. ROYALS.
